UNITED STATES PATENT OFFICE.

E LEMUEAL OSBORN, OF SEATTLE, WASHINGTON.

WAVE-MOTOR.

1,314,147.

Specification of Letters Patent. Patented Aug. 26, 1919.

Application filed October 18, 1918. Serial No. 258,700.

To all whom it may concern:

Be it known that I, E LEMUEAL OSBORN, citizen of the United States, residing at Seattle, in the county of King and State of Washington, have invented certain new and useful Improvements in Wave-Motors, of which the following is a specification.

This invention relates to improvements in wave motors and has for its principal object to provide an improved and novel wave motor device in which intermittent power of the waves is stored and transmitted continuously therefrom; in a device of the class described to provide a novel spring power storage means together with means for feeding out the stored power continuously.

Other objects will appear as my invention is more fully explained in the following specification, illustrated in the accompanying drawings and pointed out in the appended claim.

In the drawings Figure 1 is a plan view of my device. Fig. 2 is an end elevation of same with parts omitted. Fig. 3 is a sectional elevation taken along line $x-x$ of Fig. 1.

Referring more particularly to the drawings numeral 1 indicates a frame work upon which the device itself is mounted and which 30 is positioned over the water. A float 2 is positioned below the frame and receives the lifting action of the waves. Shafts 3, 4 and 5 are mounted in bearings transversely the frame work 1 and are in parallel relationship to each other with the shaft 4 directly above shaft 3. Shafts 3 and 5 are each connected to the float 2 through similar gear treads which include gear wheels 6 which mesh with pinion 7. Pinions 7 are attached 40 to shafts 4 and 5 while the gears 6 are secured to shafts 8 to which are also secured ratchet wheels 9. Racks 10 are in coöperation with opposite faces of ratchet wheels 9 and are pivotally secured at their lower ends 45 to float 2. It will be understood that the racks have their teeth running in reverse directions on opposite sides of the wheels 9 so that only one rack acts upon the wheel during the upward movement of the float 50 and the other rack acts upon the wheel during the downward stroke, thus giving the ratchet wheel a continuous motion in one direction. I employ novel means for maintaining the coöperation between the racks 55 and wheels which embodies links 11 pivoted to the frame 1 and housing the back edge of

the racks. The upper or free ends of the links 11 are held together by means of a spring 12 so that the racks are at all times yieldingly held in contact with the wheels 9 60 and when it is necessary for one of the racks to slip past the wheel on its idle stroke the link 11 yields sufficiently to permit this slippage. The shafts 3 and 4 and 5 are all geared together at their opposite ends by means of 65 gear wheels 14, 15 and 16, respectively. It will be understood that the gear wheels 14, 15 and 16 are loose upon their respective shafts and that each of the said wheels is provided with a series of pawls 17 which 70 coöperate with ratchet wheels 18, one of which is also loosely mounted upon each of shafts 3, 4, and 5. A tapering helical spring 19 is mounted upon each of the shafts 3, 4 and 5, the latter two of which are right 75 handed while the former is wound left handed. One end of each of the springs 19 is secured to one of the ratchet wheels 18 while the other ends are secured to collars 20 which in turn are secured to the shafts 80 3, 4, and 5. It will thus be seen that as the shafts 3, 4, and 5 are rotated that they wind up the springs 19 by revolving the collars 20 while the ratchet wheels 18 and wheels 15 remain stationary under the influence of 85 band brakes 21, 22 and 23, respectively, as will be more fully explained later. The band brakes are attached to levers 24, 25 and 26, respectively, which in turn are secured to brake rods 27, 28 and 29, respectively. 90 The brake rods are secured to pistons (not shown) within cylinders 30, 31, and 32, respectively. The cylinders are dash pot type brakes and each contains a spring 33 which normally holds the brake 95 in released position. It will be understood that each of the brake devices is arranged to open under a different water pressure which is supplied to the brake cylinders from a pump 34, as will be explained later. 100

The pump 34 is of the two cylinder type and is operated by a crank shaft 35 upon which is mounted a pinion 36 which meshes with a gear 37. The gear 37 is secured to a jack shaft 38 which is mounted upon bearings upon the frame 1 and upon which is secured a pinion 39. The pinion 39 meshes with gear 15 thus furnishing the power transmission between the energy stored in the coil springs and the pumps. Suction 105 pipes 40 lead to the pumps 34 and discharge pipes 41 lead from the pumps to a reservoir

(not shown). Auxiliary pipes 42 lead from one of the pipes 41 to each of the brake cylinders 30, 31 and 32 so that whenever the pressure of the water is insufficient to hold 5 the spring 33 within the brake cylinder, the brake will be released on that particular spring, thus permitting the stored energy to be transmitted to the pump thus raising the pressure. As previously stated, the brake 10 cylinders are set to release the brakes at different pressures so that energy stored in one of the springs will be used first in every case after which an additional drop in pressure 15 of the pump will release an additional spring.

While applicant is aware that tide motor and pumping devices are old art he believes that his device embodies novelty and flexibility in the means of storing energy in 20 order that the intermittent power of the tide and wave actions may be stored and consumed at a uniform rate at a later time. In this connection special consideration is given to the arrangement of springs and to 25 the means for holding the racks 10 against the ratchet wheels.

While I have shown a particular form of embodiment of my invention I am aware that many minor changes will suggest themselves to others skilled in the art without departing from the spirit and scope of my invention, and I therefore desire to avoid being limited to the exact form shown and described.

35 Having described my invention, what I

claim as new and desire to protect by Letters Patent, is:-

In a device of the class described the combination of a frame work, a float positioned beneath the said frame work, a plurality of 40 parallel shafts arranged upon the said frame work, power transmission means intermediate the said float and said shafts, whereby the reciprocating motion of the float is converted into rotary motion of the shafts, 45 ratchet wheels loosely mounted upon the said shafts, gear wheels loosely mounted upon the said shafts adjacent the said ratchet wheels and geared one with the other, pawls secured to the said gear wheels 50 and coöperating with the said ratchet wheels, whereby the ratchet wheels may move in one direction independent of the said gear wheels, coil spring means upon each of the said shafts and secured at one 55 end to the said shafts and at the other ends to the said ratchet wheels, whereby power transmitted to the shafts is stored in the spring and transmitted through the ratchet wheel to the said coils, brakes mounted upon 60 the said shafts and secured to the said gear wheels, brake cylinders connected to the said brakes, pumps geared to the first mentioned gear wheels, pipes connecting the pumps to the brake cylinders, whereby when the pressure of the pumped water drops below a pre-determined pressure the brakes are released.

In testimony whereof I affix my signature.

E LEMUEAL OSBORN.
